SPECIFICATION forming part of Design No. 21,963, dated November 8, 1892.

Application filed October 10, 1892. Serial No. 448,448. Term of patent 3½ years.

To all whom it may concern:

Be it known that I, CHARLES BOOZE, a citizen of the United States, residing at Buffalo, in the county of Erie and State of New York, have invented and produced a new and original Design for Wall-Paper, of which the following is a specification, reference being had to the accompanying drawing, forming part hereof.

10 The leading feature of this design consists of an arrangement of ornamental scrolls and lines springing from a vase-like ornament forming the center of the design and filled with flowers and leaves, as represented in the accompanying drawing. Small vines and leaves hang in festoons from the bottom of the vase-like ornament, and between the curved lines

on each side of the ornamental scrolls are small fleur-de-lis ornaments, which also form part of said design.

20 The design is arranged at regular distances on the surface of the paper and is printed in any desired color or colors or in mica or bronze and colors upon tinted paper of any desired color.
